[57] **CLAIM**

The ornamental design for a combined self-righting sinker and lure support with trailing legs, as shown.

DESCRIPTION

FIG. 1 is a perspective view of a combined self-righting sinker and lure support with trailing legs, showing our new design;

FIG. 2 is a front elevational view thereof;

FIG. 3 is a rear elevational view thereof;

FIG. 4 is a left side elevational view thereof;

FIG. 5 is a top view thereof; and

FIG. 6 is a bottom view thereof.
